UNITED STATES PATENT OFFICE.

FREDRICKA E. REUTER, OF CHICAGO, ILLINOIS.

TELEPHONE ADVERTISING NOVELTY.

Application filed June 16, 1924. Serial No. 720,195.

This invention relates to a simple and improved advertising novelty adapted to be readily mounted in place on a telephone, behind the telephone mouthpiece, and constructed in the shape of a floral design or similar article and concealing a plurality of pivoted index or directory cards arranged in any desired order and containing names and telephone numbers of subscribers with whom one has frequent intercourse.

It is an object of this invention to provide an ornamental telephone index or directory adapted to be removably engaged on the transmitter of a telephone and having telephone index cards disposed beneath an ornamental cover with the telephone mouthpiece serving as a stop for the index leaves when the same are in closed position.

It is an important object of this invention to provide a telephone advertising novelty in the form of a flower or other article adapted to carry an advertisement and having a plurality of accessible hidden telephone list cards all of which are supported on a common pivot between a back plate and decorative front pieces.

Other and further important objects of this invention will be apparent from the disclosures in the specification and drawings.

The invention (in a preferred form) is illustrated in the drawings and hereinafter more fully described.

On the drawings:—

Figure 1 is a front view of the telephone advertising novelty of this invention mounted on the transmitter of a telephone.

Figure 2 is a side view thereof.

Figure 3 is an enlarged fragmentary section taken on line 3—3 of Figure 1.

Figure 4 is a front view of the directory device in open position disclosing several of the index cards or leaves.

As shown on the drawings:—

The reference numeral 1 indicates a portable telephone stand having the customary receiver 2 and a transmitter 3. A mouthpiece 4 is threaded into the transmitter 3 and serves to hold the floral advertising novelty in place on the transmitter.

The advertising novelty in the form illustrated comprises a one piece back plate 5 of a shape to correspond to the outline of a flower or other article and carrying a pivot sleeve or thimble 6 on which a plurality of half sheets or index cards 7 are

pivotaly mounted in overlapping relation. Each of the index cards is shaped to correspond to substantially one-half of the contour of the flower and is provided with a semi-circular notch 8 to fit around the telephone mouthpiece 4 which acts as a stop for the index cards 7 when they are in closed position. Each index card 7 is arranged or printed to provide for a list of name spaces and corresponding telephone number spaces as illustrated in Figure 4. The index cards may be printed in any desired arrangement and alphabetically assembled if so desired for the sake of convenience in finding desired names and numbers.

Also pivotally mounted on the sleeve or thimble 6 in front of the index cards 7 is a pair of cover cards 9 shaped to conform to one-half the contour of a flower of selected design. Each cover card 9 is provided with a semi-circular notch 10 to engage around the telephone mouthpiece 4 when the cover cards or plates are in closed position to conceal the index cards and give the device the appearance of a flower.

Any desired form of advertising matter may be printed or otherwise applied to either one or both of the cover cards 9 to permit the device to be used as an advertising medium. If preferred the advertising matter may be placed on the index cards or on the back plate 5.

The size of the hole in the back plate is such that the threaded portion of the telephone mouthpiece will fit therein to hold the device secured to the telephone transmitter 3 against rotation.

The device may be made of cardboard, celluloid or any other desired material and of various colors to suit the taste of purchasers. The cover plates when closed give the appearance of a flower and if desired said cover plates may be covered with silk and elaborately made for use in living rooms, boudoirs and the like.

I am aware that numerous details of construction may be varied through a wide range without departing from the principles of this invention, and I therefore do not purpose limiting the patent granted otherwise than necessitated by the prior art.

I claim as my invention:—

1. A telephone advertising novelty comprising an apertured back plate having a selected contour to represent the shape of a selected flower, a plurality of notched in-

dex cards adapted to fit around the telephone mouthpiece and pivotally mounted at a common point on the back plate and having one edge also shaped to conform to the 5 shape of the selected flower, and a pair of notched cover plates pivoted at the common point and shaped to resemble the shape of a flower when the cover plates are closed to permit the notches therein to engage around 10 the telephone mouthpiece with the cover plates concealing the index cards and the back plate.

2. A telephone advertising device comprising an apertured mounting plate adapted to 15 be held in place by the mouthpiece of a telephone and having a selected contour, a pivot thimble supported thereon, a plurality of notched index cards pivoted on the thimble, and adapted to engage the telephone 20 mouthpiece as a stop and a plurality of notched cover cards of a selected configuration and design also pivoted on the thimble and adapted to conceal the index cards when the notches therof engage the 25 telephone mouthpiece.

3. A telephone index comprising a back plate having an opening therein to permit the back plate to be held in place on a telephone transmitter, a pivot thimble supported 30 on the back plate, a pair of cover plates pivoted on the thimble and having notches therein to permit the cover plates to engage against the transmitter mouth-

piece as a stop, and a plurality of index cards pivoted on said thimble between the 35 back plate and said cover plates adapted to be concealed from view behind the cover plates.

4. The combination with a telephone transmitter and mouthpiece, of a telephone 40 directory comprising an apertured back plate adapted to be clamped between the telephone transmitter and the mouthpiece, a plurality of index cards pivoted on the back plate and notched to engage against the 45 telephone mouthpiece as a stop when the index cards are in closed position, and floral front pieces also pivoted on the back plate and adapted to engage against the telephone mouthpiece as a stop when in closed position 50 to conceal the index cards, said front pieces when in closed position having the appearance of a flower with the telephone mouthpiece forming the center of the flower.

5. A telephone directory of the class described comprising a mounting plate and a plurality of overlapping notched cards pivoted 55 at a common point on the mounting plate and giving the directory when closed a predetermined form, said cards being notched for the purpose of engaging the telephone mouthpiece as a stop.

In testimony whereof I have hereunto subscribed my name.

FREDRICKA E. REUTER.
